COMB FOR HAIR CLIPPERS

Battista Pasquesi, Highwood, Ill., assignor, by
direct and mesne assignments, of one-half to
Adelmo Giorgi, Highwood, Ill.

Application January 27, 1949, Serial No. 73,030

16 Claims. (Cl. 30—201)

1

The present invention relates to an improved arrangement for yieldably mounting or attaching a hair comb to a hair clipper, thereby to permit relative tilting movement between the clipper head and the comb for the purpose of varying the depth of cut made by the clipper during each sweep or stroke thereof. The arrangement is such that the hair comb may be quickly mounted on or detached from clippers of either the hand-operated or the mechanically operated type. When in its mounted position the comb has a yieldable connection with the clipper, such connection being defined by a spring metal strip attached at its ends respectively to the clipper head and to the comb. For the purpose of increasing the yieldability of such connection the metal strip is preformed with an S-shaped bend in its central region. This provides approximately straight or flat terminal regions extending in opposite directions which may be removably mounted respectively on the clipper head and the comb.

One of the principal objects of this invention is to simplify the construction of a comb attachment for hair clippers such as contemplated herein, and to improve the efficiency and operation of such attachment.

Another primary object resides in providing a yieldable connection between the clipper head and the comb, such connection being defined by a structurally separate spring metal strip the terminal regions of which strip are demountably engaged with suitable guide means carried respectively by the comb and by one of the members of the clipper head.

Still another object hereof is to provide a novel hair comb which is characterized by having thereon suitable guide means preferably molded integrally with the back thereof, and constructed to slidably receive a terminal region of a spring strip for effecting a yieldable connection with the clipper head.

A further object is to provide novel latch means which are cooperatively associated with the guide members on the comb and on the spring metal strip, such latch means being effective to permit the comb to slide to different positions with respect to the cutter and guard on the clipper head, and to be releasably held by the latch in any selected position within the limits of such sliding movement.

Other objects, aims and advantages of the invention contemplated herein will be apparent to persons skilled in the art after the construction and operation of the present improvements are understood from the within description.

2

It is preferred to accomplish the numerous objects of this invention and to practice the same in substantially the manner hereinafter fully described and as more particularly pointed out in the appended claims. Reference is now made to the accompanying drawings that form a part of this specification.

In the drawings:

Fig. 1 is an enlarged view showing a side elevation of a clipper head with the present improvements thereon;

Fig. 2 is a fragmentary perspective of the novel comb showing the guide and a portion of the latch means thereon;

Fig. 3 is a perspective of the terminal region of the spring strip for coaction with the comb guide and latching means;

Fig. 4 is a view of the comb, similar to Fig. 2, and showing an alternative form of guide with latch means thereon;

Fig. 5 is a rear edge view looking at the assembly shown in Fig. 1 and viewed in the plane of line 5—5 thereon;

Fig. 6 is a fragmentary side elevation showing a simplified comb mounting arrangement;

Fig. 7 is a view looking at the underside of the clipper head shown in Fig. 6 along the plane of line 7—7; and

Fig. 8 is a side edge view illustrating an arrangement for mounting the spring strip on a cutter guard.

Fig. 9 is a fragmentary perspective view of a further modification of the novel comb plate guide means.

The drawings are to be understood as being more or less of a diagrammatic character for the purpose of disclosing typical or preferred embodiments of the improvements contemplated herein, and in said drawings the same reference characters identify similar parts in the different views.

As seen in Fig. 1 the assembly 10 at the distal portion of the hair clipper comprises a fixed toothed guard 11 across which a tooth cutter plate 12 is rapidly vibrated by suitable actuating mechanism that is usually housed in a holder or casing 13. The hair comb 14 is approximately the same width as the guard 11 and it is preferably arranged in a plane that is oblique to the plane of the guard so that said comb inclines towards the apices of the guard teeth. There is a yieldable connection between the comb and guard and this connection is such that the operator may readily adjust the comb by sliding it forwardly or rearwardly to change the relationship of the comb

55 to the cutting mechanism. Also, while perform-

ing a cutting operation the operator may tilt the clipper up or down or may cant it sidewise, in order to graduate the length of hair remaining on the scalp. It will be understood that during clipping operations, the comb is presented flat against the scalp and the whole assembly is guided by the operator in the direction for making the proper or desired kind of cut or the length thereof. It is therefore apparent that an operator requires but little skill to successfully manipulate the structure in a manner to neatly trim hair in a graduated length upwardly from the lower region of the neck to the pate or crown of the head, as well as around and above the ears and toward the temples of the head.

In its preferred forms, illustrated in detail in Figs. 1 through 5, the yieldable connection between the clipper guard 11 and the comb 14 comprises a structurally separate strip 15 of spring metal. The intermediate or central region is performed into a pair of oppositely formed or reverse bends 16 and 17 which together define an ogee or S-shape formation to increase the yieldability of the strip and permit the tilting movements of the clipper with respect to the comb as above suggested. The terminal regions 18 and 19 of the metal strip extend in opposite directions from the S-shape formation and they are generally straight or flat to permit sliding thereof while engaging portions of the guard and comb respectively.

For the purpose of securing the above-mentioned sliding relationship an elongate metal mounting plate 20, having an angular channel 21 therein, is suitably secured to the back surface of the guard 11 so that the open portion of the channel is next to the guard and provides therewith a pocket-like guide into which the terminal region 18 is adapted to fit. An off-set 22 at the end of terminal 18 engages the end edge of the channel and holds the strip against accidental dislodgement but at the same time permits the terminal 18 to be forcibly withdrawn through the channel pocket 21 to disassemble the clipper from the guide. Plate 20 may be welded to the guard plate, or as shown in Fig. 7, open slots 23 are made in this mounting plate for inserting the latter around the shanks of longer screws 24 which replace the usual screws for attaching the guard to the cutter head. After being positioned in place retainer nuts 25 are tightened onto screws 24 to hold the plates in assembly.

In its preferred form as shown in Fig. 3 the second terminal 19 of the spring strip is performed with downturned inwardly extending flanges 26 of L-section which extend along its longitudinal edges. Between the bend 16 and the adjacent ends of these flanges there is a transverse bend or rib 27 which defines one portion of a latch arrangement. The comb 14 has an elongate guide 28 the sides of which are undercut as at 29 to provide oppositely extending wings that are slidably embraced by the L-shaped flanges 26 of the terminal region 19 of the spring strip.

The outer or upper face of guide 28 has transverse serrations 31 one of which is engaged by the rib or bend 27 on the spring strip 15 to latch the comb in different positions within the limits of its sliding movement while being supported on the strip by the holder flanges 26. It will be understood that the comb structure above described may be readily molded from a suitable plastic composition with the attaching member 28 integral with its back portion. It is contemplated

that the attaching member may be such as shown in Fig. 4 which comprises a metal strip 32 formed with a longitudinal depression 33 of U-section and having outwardly extending side flanges 34 that are serrated at 35 in the same manner as in the preferred form shown in Fig. 2. This metal strip 32 is secured to the back of the comb by small rivets or attaching pins 36, and functions as a sliding guide for the comb when the strip is mounted thereon.

In the arrangement shown in Fig. 6 the comb has a narrow plate 37 riveted to it with its channel 38 facing and covered by the back of the comb. In this simplified arrangement the terminal region 19 of strip 15 has a bowed shape as at 39 to frictionally contact at least the top and bottom walls of the pocket formed by the channel piece laying against the surface of the comb. The extreme end of the spring strip has an offset deformation or lip 40 to project outside said pocket to retain the comb against accidental dislodgement but at the same time permitting the comb to be adjustably moved or slid along the terminal region 19 in the same manner as in the other forms shown.

An alternative arrangement for mounting the spring strip 15 on the clipper head is shown in Fig. 8 wherein the guard 11 is formed with a socket 41 extending inwardly from the rear edge of said guard and disposed somewhat oblique to the faces of the guard. Only slight clearance is presented between the socket walls and the terminal region 18 of the spring strip to prevent any relative sidewise or longitudinal movement of the comb mounting devices and the clipper.

It is contemplated that the straight end region of the spring strip 15, which assembles with the hair comb 14, be wider than the remaining portion of the strip as shown at 19a in Fig. 9. The comb has a guide 42 of channel cross-section secured to its back, said guide having L-shape side edges the lateral flanges 43 of which extend towards each other to define a longitudinal slot or throat 44, to receive the arcuately bent portion 16 of the spring connecting strip 15. The up-standing flanges 45 of the L-shape edges of the guide are spaced apart a distance to provide a minimum of clearance for the wide head 19a of the strip, and the body portion of the guide is upwardly bowed as at 46 to bear against the under surface of said head to urge the side margins thereof into frictional contact against the proximate surfaces of the inwardly extended flanges 46. This permits the comb to be slidingly adjusted with respect to the distal region of the clipper head and to be maintained in position by the three regions of frictional contact between the head 19a and the guide 42. The guide is secured in place by tabs or ears 47, at its opposite ends which are pinned as at 48 to the comb. For preventing the comb 14 being moved too far rearwardly, the forward tab or ear, which is bent down to lie between the roots of the comb teeth, is formed with an abutment 49 which acts as a stop when contacted by the end edge of the wider head portion 19a of the spring strip 15.

It is apparent from the foregoing that while cutting hair the comb will glide flat against the scalp and the clipper may be tilted as desired to graduate the cut, or the clipper may be canted sidewise as indicated by the arrows and the dotted lines in Fig. 5 to facilitate removing hair around and above the ears. As a result of this arrangement considerable time is saved and a large amount of labor is eliminated when cutting hair.

in different styles, and it has been found in actual experience that only a few minutes are required to complete a hair cutting operation. The manner of manipulating the device is so simple that an inexperienced person is able to cut hair efficiently and satisfactorily with either an automatically operated or a hand operated hair clipper on which the present hair comb arrangement is mounted by means of structures such as disclosed herein.

While the improvements have been described in detail in the typical or preferred embodiment, it will be apparent to persons skilled in the art, after understanding the construction and operation of this assembly, that changes and modifications may be made therein without departing from the spirit or scope thereof. It is aimed in the appended claims to cover all such changes and modifications.

What is claimed is:

1. The combination with a clipper head having a toothed fixed guard; of a hair comb arranged in spaced relation to said guard; and means for detachably mounting said comb on said guard for effecting relative tilting movement therebetween and sliding movement of said comb with respect to said guard, said means comprising guide means on said guard; guide means on said comb; a structurally separate spring metal strip the end regions of which are slidably received by the respective guide means on said guard and said comb; an S-shape bend in said strip intermediate its guided end regions, said bend defining a yieldable connection between said comb and said clipper head for effecting the aforesaid relative tilting movement; and latch means cooperatively associated with said comb and said spring strip for maintaining said comb in a plurality of positions within the limits of its sliding movement.

2. The combination with a clipper head having a toothed fixed guard; of a hair comb arranged in spaced relation to said guard; and means for detachably mounting said comb on said guard for effecting relative tilting movement therebetween, said means comprising guide means on said guard; a guide member on said comb having longitudinally extending flanges; a structurally separate spring metal strip a first end region of which is slidably received by the guide means on said guard; inturned flanges on the second end region of said strip and slidably engaged with the longitudinal flanges on the guide member on said comb; the intermediate region of said strip being bent to define a yieldable connection between said comb and said clipper head for effecting the aforesaid relative tilting movement; and means releasably latching said comb in a plurality of positions within the limits of its sliding movement.

3. The combination with a clipper head having a toothed fixed guard; of a hair comb arranged in spaced relation to said guard; and means for detachably mounting said comb on said guard for effecting relative tilting movement therebetween, said means comprising guide means on said guard; a guide of T-shape on said comb; a structurally separate spring metal strip a first end region of which is slidably received by the guide means on said guard; L-shape flanges along the second end region of said strip in slidably engagement with the arms of said T-shape guide on the comb; a bent region in the intermediate portion of said strip to define a yieldable connection between said comb and said clipper

head for effecting the aforesaid relative tilting movement; serrations on said T-shape guide; and means on said strip engageable with said serrations for maintaining said comb in a plurality of positions within the limits of its sliding movement.

4. In combination with a clipper head having a fixed guard, and a cutter vibratory thereon; of a hair comb arranged in spaced relation to said

10 guard; and means detachably mounting said comb on said clipper head comprising a spring metal strip having approximately straight end regions and being bent in its intermediate region; means on said guard for receiving one end region of said strip; and guide means on said comb for slidably receiving a second end region of said spring strip; said strip defining a yieldable connection between said comb and said clipper head.

5. In combination with a clipper head having a toothed fixed guard, and a cutter vibratory thereon, said guard having a pocket extending in the general direction of the guard teeth; of a hair comb arranged in spaced relation to said guard; and means for detachably mounting said comb on

25 said clipper head for effecting relative tilting movement therebetween, said means comprising a structurally separate spring metal strip having a central region defined by a bend of S-shape, and having approximately straight end regions

30 extending in opposite directions from said central region, a first of said end regions being removably inserted in said guard pocket; guide means on said comb for slidably receiving a second end region of said spring strip, whereby said comb may be slidably moved with respect to the distal end of said clipper head; and latch means releasably maintaining said comb in any of a plurality of positions within the limits of its sliding movement.

40 6. In combination with a hair clipper; a hair comb arranged in spaced relation to the distal region of said hair clipper; a structurally separate spring metal strip having two reverse bends therein and end regions extending in opposite directions away from the respective bends; means mounting a first end region of said strip on said hair clipper; means mounting a second end region of said strip on said comb for sliding movement of said comb with respect to said strip.

50 7. An arrangement as defined in claim 6, including latch means cooperatively associated with the comb and a proximate end region of the strip for releasably holding said comb in different positions within the limits of its sliding movement.

55 8. In combination with a hair clipper; a hair comb arranged in spaced relation to the distal region of said hair clipper; a structurally separate spring metal strip having end regions extending away from each other; means mounting a first end region of said strip on said hair clipper; means mounting a second end region of said strip on said comb, said last mentioned mounting means being comprised of a member on said strip cooperatively associated with a member on said comb for effecting reciprocal sliding movement of said comb with respect to the work portion of said hair clipper.

70 9. An arrangement as defined in claim 8 including latch means releasably holding said comb in different positions within the limits of its sliding movement.

10. In combination with a hair clipper; a hair comb arranged in spaced relation to the distal

75 region of said hair clipper; a structurally sepa-

rate spring metal strip having end regions extending away from each other; means mounting a first end region of said strip on said hair clipper; a guide on said comb slidably receiving a second end region of said strip; and means on said guide effecting a frictional engagement with the coacting second end region of said spring strip.

11. An arrangement as defined in claim 10, wherein the second end region of the spring strip has a wide head portion cooperatively associated with the guide; and the guide has a deformed body portion which engages said head portion for effecting frictional engagement therewith.

12. An arrangement as defined in claim 10, wherein the guide is of channel section with intertwined flanges which define a longitudinal slot; and the spring strip has its second end region formed with a wide head guided by said flanges, the portion of the spring strip proximate said head being extended through said slot.

13. An arrangement as defined in claim 10, wherein the guide has a slot to receive the spring strip and there is a wide head on the strip slideable in the guide; the body of the guide being bowed upward towards the slot to effect frictional contact with the head on the strip.

14. The combination with a hair clipper; of a comb arranged in spaced relation to said clipper; and means detachably mounting said comb on said clipper for effecting relative tilting movement therebetween and also sliding movement of said comb with respect to said clipper, said means comprising guide means on said comb; a structurally separate leaf spring having a reversely bent region defining a first end portion attached to said clipper, and a second end portion slidably received by said guide means on the comb, said bent region providing a yieldable connection between said clipper and said comb for effecting the aforesaid relative tilting movement; and re-

leasable holding means cooperatively associated with said comb and the proximate end region of said leaf spring for maintaining said comb in any selected position within the limits of its sliding movement.

15. In combination with a hair clipper; a hair comb arranged in spaced relation to the distal region of said hair clipper; a structurally separate spring metal strip having end regions extending away from each other; means mounting a first end region of said strip on said hair clipper; means mounting a second end region of said strip on said hair comb for sliding movement with respect to said strip; and latch means releasably holding said hair comb in different positions within the limits of its sliding movement.

16. The combination with the head of a clipper having a fixed guard and a cutter vibratory thereon; of a hair comb arranged in spaced relation to said guard; and means yieldably connecting said comb to said clipper head for effecting tilting movement therebetween, said means comprising a structurally separate spring metal strip having thereon a reverse bend intermediate its ends, and having approximately straight end regions extending away from said bend; means removably connecting said end regions of said strip respectively to said guard and to said comb and effecting sliding movement of the comb with respect to said clipper guard, the connecting means for the strip and comb being particularly characterized by cooperatively associated releasable elements on said strip and said comb.
